UNITED STATES PATENT OFFICE

132,566

DESIGN FOR A SUIT

Rubin Troffkin, New York, N. Y.

Application March 3, 1942, Serial No. 106,060

Term of patent 3½ years

To all whom it may concern:

Be it known that I, Rubin Troffkin, a citizen of the United States of America, residing in New York city, county of New York, and State of New York, have invented a new, original, and ornamental Design for a Suit, of which the following in a specification, reference being had to the accompanying drawing, forming part thereof, wherein,

I claim:

The ornamental design for a suit, substantially as shown.

RUBIN TROFFKIN.
